UNITED STATES PATENT OFFICE.

WILLIAM L. WILLIAMS, OF WINONA, MINNESOTA.

ICE-VELOCIPED.

SPECIFICATION forming part of Letters Patent No. 606,479, dated June 28, 1898.

Application filed July 23, 1897. Serial No. 645,725. (No model.)

To all whom it may concern:

Be it known that I, WILLIAM L. WILLIAMS, a citizen of the United States, residing at Winona, in the county of Winona and State of Minnesota, have invented certain new and useful Improvements in Velocipedes; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to velocipedes, and is directed more particularly to improvements in machines of this character which are adapted for propulsion over ice and snow-covered ground, the object of the invention being to provide a comparatively simple and inexpensive construction of machine capable of being foot-propelled with the expenditure of ordinary labor and of being readily and reliably governed.

Another object of the invention is to provide in a machine of this character means for insuring, when desired, a constant contact between the driving-wheel and the surface over which the machine is propelled, regardless of the inequalities of the ground, whereby the power exerted is made available at all times; also, means for bringing at will the driving-wheel away from contact with the ground for coasting purposes; also, means for checking or breaking the momentum of the machine, and also means by which the machine may be readily transported over bare ground.

The nature of my invention will be clearly understood by reference to the following detailed description, which is to be read in connection with the accompanying drawings, in which—

Figure 1 is a side elevation of my improved machine, and Fig. 2 is a top plan view.

Referring to the said drawings by letter, A denotes the frame of the machine, which is constructed from tubing and comprises the lower member a , to which is attached the steering-runner B, the seat-post a' , which carries the seat or saddle c, the steering-post a^2 , the crank-hanger a^3 , in which is journaled the crank-shaft carrying the pedal-cranks d and the sprocket-wheel d' , and the rear fork a^4 ,

which extends from the crank-hanger to the axle e of the driving-wheel E. On said axle is a second sprocket-wheel e' , which is connected by a chain e^2 with the sprocket-wheel d' . At the sides of the frame are runners f, which are curved at their forward ends and secured to the steering-post a^2 by a direct connection and by brace members g. Near the rear ends of the runners connection is made with the frame by brace members g' . The runners are preferably of wood, with the exception of the tread portion, which is provided with a steel shoe f' .

From each of the rear brace members g' there extend rearwardly two arms g^2 g^3 , the outer ends of which are slotted for adjustable connection with a guide-bracket H, which is curved in the arc of a circle, with the axle of the wheel d' as the center. The rear fork is also adjustably connected with the guide-brackets. In the slots h of the brackets H are movably arranged bearing-blocks i, in which is journaled the axle of the driving-wheel.

i' is a rod which is connected at one end to a block i and is movable in the slot h and through an opening in the bracket. A coiled spring j encircles this rod and is interposed between the block i and a tension screw-rod j' in the upper end of the bracket, which rod has a governing-nut j^2 , confined in a housing h' on the bracket. The function of the springs j is to insure a constant contact of the driving-wheel with the ground or surface over which it is propelled, regardless of inequalities of the latter, the springs tending to press the wheel downward against the ground and permit it to rise and fall with such inequalities independent of the movements of the rest of the structure. The tension-rods j' are employed for adjusting the strength of the springs to suit the different weights of riders, as will be understood. The adjustable connection between the arms g^2 , the rear fork, and the guide-brackets is for the purpose of tightening or loosening the sprocket-chain, the slots in said arms permitting the movement bodily of the brackets, driving-wheel, and rear sprocket-wheel either forwardly to loosen the chain or rearwardly to tighten the same. Pivotedly secured to one of the rear brace members is a bell-crank lever k, one

arm of which carries a handle k' , while the other arm has rod connection with a block k^2 , movable in the slot h of the bracket H . The handle is located conveniently near the seat or saddle in order that the rider may readily manipulate the same to effect the elevation of the driving-wheel above the surface of the ground for coasting purposes. This is accomplished by a pull on the lever, which 10 brings the block k^2 into contact with the bearing-block, and thereby raises the latter and the wheel to the desired height against the action of the springs j . Means are provided for locking the wheel in its raised position in 15 the shape of a spring-catch k^3 , which is secured to the upper end of the rear brace member and which engages the handle-arm of the lever k . The driving-wheel is provided on its periphery with a plurality of removable 20 blades e^2 and spikes e^3 , the former being employed for propulsion over snow-covered ground and the latter for propulsion over ice. The blades and spikes are made to be removable in order that the wheel may be provided 25 with spikes or with blades, dependent upon circumstances, and in some instances, owing to the character of the ground, I may employ both together, either equal or different in number.

30 The frame member a has at its forward end a head a^5 for the stem b of the steering-runner B , which runner is secured in the bifurcated lower end b' of said stem. Between the shoulder formed by the bifurcation and 35 the head a^5 is a spring b^2 , coiled around the stem. This construction allows of the movement of the runner B independent of the frame for the purpose of insuring contact between the runner and ground at all times, regardless of surface inequalities. The runner 40 B is employed to steer the machines, and means are employed for manipulating said runner through the movement of the handle-bars l , consisting of rods $m m$, which are connected at their forward ends to yoke b^3 , fixed to the upper end of the stem b , and at their rearward ends to a yoke l' , carried by the steering-stem l^2 , which stem is rotatably supported in the post a^2 and is connected at its upper end with the handle-bars. The rods m 45 are made to be adjustable in length by the employment of turnbuckles m' or similar devices.

50 n denotes the brake by which the momentum of the machine is controlled, said brake consisting of a bent lever pivoted at n' to the frame and provided at the end of its lower arm with spurs n^3 , which when lowered into contact with the ground effect the retarding 55 and stoppage of the machine. The other arm n^3 of the lever is connected to the lower end of the operating-rod n^4 , which is movable in a guide n^5 on the frame and carries at its upper end a handle n^6 , adjacent to the handle-bars. The brake is operated by raising the 60 handle n^6 , which depresses the lower end of the lever and causes the spurs to contact with

the ground with sufficient pressure to retard and stop the movement of the machine.

As a means for readily transporting the machine over bare ground I provide four wheels $o o$, each of which is mounted to rotate on the lower end of an arm o' , movable in guides $o^2 o^2$ on the brace members or on any other suitable parts of the frame. These wheels are adapted 75 to be raised to be clear of the ground or to be lowered to a point below the runners and driving-wheel to elevate the whole structure for ready transportation.

The machine is propelled in a manner similar to that employed in operating an ordinary velocipede in that motion is imparted to the driving-wheel by the rotation of the forward sprocket and through the chain-and-sprocket connection with said driving-wheel. The 85 spring connection between the driving-wheel and the frame insures the proper contact of the wheel with the ground, and no loss of power ensues and the machine is propelled evenly. The curved form of the bracket in 90 which the wheel-axle is movable preserves the adjusted tension of the sprocket-chain, and the means employed for regulating the tension of the spring enables the adjustment of the parts to suit different weights of riders. 95 The means employed to effect the tightening or loosening of the sprocket-chain are simple and easily manipulated, and all of the other adjustments may be made in a comparatively short time and without the exercise of skill. 100 Moreover, the means for raising the driving-wheel for coasting purposes and for steering and operating the brake are within easy reach of the rider and may be operated with the expenditure of but little power. 105

I claim as my invention—

1. In a machine of the class described, the combination with a frame carrying runners, of a driving-wheel, sprocket wheel and chain mechanism for operating said driving-wheel, 110 brackets adjustably connected with the frame, blocks movable in said brackets and affording bearings for the driving-wheel axle, springs for controlling said blocks, and means for adjusting the tension of the springs, substantially as set forth. 115

2. In a machine of the class described, the combination with a frame carrying runners, of a driving-wheel journaled in spring-controlled movable bearings, means adjustably 120 connecting the bearings with the frame, and means for elevating said wheel above the runners, consisting of a hand-operated lever having rod connection with said bearings, and a lock for said means, substantially as described. 125

3. In a machine of the class described the combination with a frame carrying runners, of a driving-wheel provided on its periphery with removable and interchangeable blades 130 and spikes, sprocket wheel and chain mechanism for operating said driving-wheel, curved brackets carrying spring-controlled movable bearings for the axle of the driving-wheel,

arms adjustably connecting the brackets with the frame, and means for elevating said wheel above the runners consisting of a hand-operated lever having rod connection with the 5 bearings, and a lock for said means, substantially as described.

4. In a machine of the class described, the combination with the frame and driving-wheel, of brackets in which the said wheel is 10 journaled, and arms secured to the frame and having adjustable connection with said brackets, substantially as described.

5. In a machine of the class described the combination with a frame carrying runners, of wheels mounted on arms slidably connected 15 with the frame and adapted to be moved to a position below the runners, substantially as and for the purpose set forth.

In testimony whereof I affix my signature in presence of two witnesses.

WILLIAM L. WILLIAMS.
